UNITED STATES PATENT OFFICE.

RICHARD F. GILE, OF CLIFTONDALE, MASSACHUSETTS, ASSIGNOR, BY MESNE ASSIGNMENTS, TO GEORGE K. WOODWORTH, TRUSTEE, OF BROOKLINE, MASSACHUSETTS.

INTERNAL-COMBUSTION ENGINE.

1,335,326.

Specification of Letters Patent. Patented Mar. 30, 1920.

Application filed May 9, 1916. Serial No. 96,424.

To all whom it may concern:

Be it known that I, RICHARD F. GILE, a citizen of the United States, and a resident of Cliftondale, in the county of Essex and State of Massachusetts, have invented a new and useful Improvement in Internal-Combustion Engines, of which the following is a specification.

My invention relates to internal combustion engines and more especially to double-acting engines of the combined pump and motor cylinder type, and its object is to provide a simple and efficient means connected directly to the main cross-head for controlling the motion of the sub-piston.

The drawings which accompany and form a part of this specification show an illustrative embodiment of my invention, but it is to be understood that the construction herein particularly described may be widely varied without departing from the scope of my invention as defined by the appended claims.

In the drawings—

Figure 1 is a central longitudinal section of a single-acting engine embodying my improved sub-piston control. Fig. 2 is a central longitudinal section taken on the line 2—2 of Fig. 1. Fig. 3 is a transverse section taken on the line 3—3 of Fig. 1.

Figs. 4, 5, 6 and 7 are diagrams showing the positions of the moving parts at various points in the cycle.

In the particular drawings selected for more fully disclosing my invention, 1 represents a frame having a horizontal crank-shaft 2 suitably journaled therein and supporting the cylinder 3, the ends of which, in the present instance, are provided with a number of parallel fuel passages or flutes 4, 4' arranged lengthwise in its bore and communicating with the combustion chambers A A' respectively. While I do not limit myself to the number of flutes that may be employed I have found that from sixteen to twenty, more or less, give good results. Arranged to reciprocate within the cylinder is a sub-piston consisting of two heads 5, 5' rigidly connected by the rods 6, and the lower head is connected to or integral with the hollow piston rod or sleeve 7, which in turn is secured to the cross-head 8 guided in the ways 9 on the engine frame. Arranged to reciprocate within the cylinder and between the heads

of the sub-piston is a power piston 10 connected to or integral with the piston-rod 11 which passes axially through the lower head of the sub-piston and the hollow piston-rod 7, and is secured at its lower end to the cross-head 12 guided by the ways 9. The hub of the pitman 13 is pivotally connected to the cross-head 12 by the hollow wrist pin 14 arranged between the sides of said cross-head and inclosing the rock-shaft 15, the ends of which project beyond the cross-head and to which the arms 16 are secured by the keys 17. The box of the pitman engages the wrist pin 18 of the crank 19, which, as shown, is integral with the power shaft. 70

Pivotedly connected with studs 20 projecting from the cross-head 8 are connecting rods 21, the lower ends of which pivotally engage studs 22 extending outwardly from the arms 16, the inner faces of which are 75 provided with slots 23 adapted to receive the sliding blocks 24 pivoted to the arms 25 of the rock-shaft 26, the latter being journaled in the engine frame.

The cylinder is provided with exhaust 80 passages 27, 27' controlled by the inwardly opening valves 28, 28' normally held on their respective seats by the springs 29, 29' which surround the valve stems and have their ends bearing against the outer walls 85 of the exhaust passages and the collars 30, 30' on the valve stems. Any suitable mechanism may be employed to raise the valves from their seats at the proper times.

A fuel inlet 31 located substantially midway between the ends of the cylinder may be connected to any suitable source of fuel.

By means of the flutes or fuel passages 4, 4' I secure an intimate and substantially perfect mixture of the fuel charge and this 95 results in practically complete combustion. As the power piston approaches the advancing head of the sub-piston, the charge contained in the space between these two elements is compressed and forced by such 100 compression around said head through the restricted passage afforded by the flutes or fuel passages and is shot with great force against the cylinder head in a number of relatively small streams.

An explosion of the compressed charge in either combustion chamber acts directly on the adjacent head of the sub-piston and by the latter is communicated to the power piston. It is absolutely necessary that the 110

- two pistons shall travel at the same rate of speed without the slightest relative movement until the sub-piston shall have covered the inner ends of the adjacent set of flutes.
- 5 The reason for this will be obvious from an inspection of Fig. 1 in which the parts are shown in the position occupied immediately prior to ignition in the combustion chamber A. Should the power piston begin to
- 10 move away from the upper head 5 of the sub-piston before the latter covers the inner ends of the flutes 4, a portion of the effect of the explosion will be exerted against the lower face of said head 5 in opposition to the force exerted on the upper face thereof.
- 15 It is essential also that the subsequent relative movement between the pistons be created positively.

The positive relative movement of the sub-piston with respect to the power piston is created by the main cross-head 12 which communicates the necessary motion to the sub-piston through the arms 16 and connecting rods 21, such motion being regulated by

20 the rock-shaft 26 and arms 25 thereof which coöperate with said arms 16 by the block and slot connection 24, 23 above described.

When both pistons are at the upper end of their strokes, as shown in Figs. 1 and 2, 30 and the charge compressed in the combustion chamber A, the valve 28 being closed and the valve 28' open or about to open, the charge is fired and the resulting explosion causes both pistons to descend at the same initial rate of speed and without any relative movement until the crank which rotates in the direction of the arrow has arrived at about 90 degrees from its initial position shown in Fig. 1 whereupon the sub- 35 piston begins to lag and the power piston, continuing its descent, begins to move away from its upper head and approach its lower head. It will be understood however that by varying the proportions of the several 40 elements the point at which the pistons begin to separate may be correspondingly altered. The sub-piston on its down-stroke will drive the burnt gases of the preceding explosion out of the combustion chamber A' 45 and through the exhaust passage 27'. As shown in Fig. 1, the blocks 24 are at or near the outer ends of their respective recesses 23 when the sub-piston is in explosion position at the upper end of its stroke, and, 50 as will be obvious, said blocks will move toward the inner ends of said recesses as the cross-head 12 descends until shortly after the crank has passed to the position shown in Fig. 4, whereupon said blocks 55 will again travel toward the outer ends of said recesses. When the crank is about 90 degrees from initial position (see Fig. 5) the blocks 24 have arrived at the outer ends of their recesses, and thereafter and until 60 the crank is 180 degrees from initial posi-

tion the arms 25 remains practically stationary and the arms 16 swing around the pivotal connection between said arms 25 and the blocks 24 (see Figs. 6 and 7), thereby retarding the speed of the sub-piston. 70 When the sub-piston has reached the end of its down-stroke, the head 5' occupies the same position with respect to the adjacent flutes 4' as the head 5 with respect to the flutes 4 in the position shown in Fig. 1, the blocks 24 being at the outer ends of their coöperating recesses, and the power piston has arrived at the end of its down-stroke, the lower face of said power piston 75 at this instant being substantially in contact with the upper face of the lower head 5'.

It will be noted that while the relative movement of the pistons is created positively, the sub-piston is free from the moment of explosion until the moment the 85 blocks 24 reach the ends of their recesses, and that therefore the sub-piston is under positive control throughout a substantial portion of the cycle.

Immediately after the power piston on 90 its down-stroke has uncovered the fuel inlet 31, the retardation of the sub-piston and the consequent relative movement between it and the power piston begins, and such relative movement creates a partial vacuum 95 within the trailing end of the sub-piston, drawing a charge of fuel through said inlet into the space between the head 5 of the sub-piston and the upper face of the power piston. At the same time the power 100 piston compresses the charge in the advancing end of the sub-piston, the space between the lower head 5' and the lower face of the power piston, a charge of fuel having been drawn into said space on the preceding up-stroke of the pistons. A portion of this charge so compressed by the power piston 105 passes through the flutes 4' into the combustion chamber A' and pneumatically expels the small remaining portion of the 110 burnt gas in said combustion chamber that was not mechanically expelled by the action of the sub-piston, thereby completing the scavenging of said combustion chamber.

The valve 28' now closes and the power 115 piston continues its downward stroke, further compressing the charge and driving the same with great force through the flutes 4' into the combustion chamber A' thereby shooting the charge against the cylinder 120 head in a plurality of relatively small streams.

The compressed charge is now exploded, the valve 28 opening slightly prior to the explosion. Both pistons rise at the same rate 125 of speed until the crank has advanced about 270 degrees from initial position whereupon, by virtue of the mechanism already described, the speed of the sub-piston is retarded and relative movement between the 130

- pistons begins, such relative movement effecting the compression of the charge in the advancing end of the sub-piston and the induction of a charge in its trailing end.
- 5 The relative positions of the several linkage elements during the upstroke are substantially the same as on the down stroke. The scavenging of the combustion chamber A is effected mechanically and pneumatically in 10 the manner above set forth with reference to the chamber A' and the charge compressed between the upper face of the power piston and the upper head 5 of the sub-piston is driven through the flutes 4 into the combustion chamber A in the manner and with the result above specified in connection with the down-stroke of the piston. Ignition then occurs again and the cycle is repeated, there being one explosion at each end of every 15 stroke or two per revolution of the crank-shaft.
- While I have described in detail the relative movement of the parts which I have found to be satisfactory in practice, it will be understood that I do not limit myself 20 specifically thereto, for said parts may be variously adjusted and timed and other cycles may be effected.
- I claim:
- 30 1. An internal combustion engine comprising a cylinder, a power piston and a sub-piston both arranged to reciprocate within said cylinder, a cross-head, means connecting said power piston to said cross-head, and means connected directly to said cross-head for retarding the speed of said sub-piston near the end of its stroke.
2. An internal combustion engine comprising a cylinder, a power piston and a sub- 40 piston both arranged to reciprocate within said cylinder, a cross-head, means connecting said power piston to said cross-head, and means connected directly to said cross-head for permitting movement of said pistons at the same initial rate of speed without relative movement and for causing, subsequently, positive relative movement between the same.
3. An internal combustion engine comprising a cylinder, a power piston and a sub- 50 piston both arranged to reciprocate within said cylinder, a cross-head, means connecting said power piston to said cross-head and means connected directly to said cross-head for permitting movement of said piston initially at the same rate of speed without relative movement and for causing said pistons, subsequently, to move at different rates of speed.
4. An internal combustion engine comprising a cylinder, a power piston and a sub- 60 piston both arranged to reciprocate within said cylinder, a cross-head, means connecting said power piston to said cross-head, means connected directly to said cross-head for 65 permitting movement of said pistons at the same initial rate of speed without relative movement, and for causing, subsequently, positive relative movement between the same, and means whereby the charge of fuel 70 in said cylinder is transferred under pressure from the space between said pistons through a restricted passage to the combustion chamber.
5. An internal combustion engine comprising a cylinder, a power piston and a sub-piston both arranged to reciprocate within said cylinder, a cross-head, means connecting said power piston to said cross-head, means connected directly to said cross-head 75 for permitting movement of said pistons at the same initial rate of speed without relative movement, and for causing, subsequently, positive relative movement between the same, and means whereby the charge of fuel 80 in said cylinder is mixed during compression.
6. An internal combustion engine comprising a cylinder, a power piston and a sub-piston both arranged to reciprocate within said cylinder, a cross-head, means connecting said power piston to said cross-head, means connected directly to said cross-head for permitting movement of said pistons at the same initial rate of speed without relative movement and for causing, subsequently, positive relative movement between the same, and means whereby the charge of fuel 85 in said cylinder is transferred under pressure from the space between said pistons to the combustion chamber in a plurality of relatively small streams.
7. An internal combustion engine comprising a cylinder having a plurality of fuel passages arranged lengthwise in its bore at one end thereof, a power piston and a sub-piston both arranged to reciprocate within said cylinder, a cross-head, means connecting said power piston to said cross-head and means connected directly to said cross-head 90 for permitting movement of said pistons at the same initial rate of speed without relative movement and for causing, subsequently, positive relative movement between the same.
8. An internal combustion engine comprising a cylinder having a plurality of fuel passages arranged in its bore near one end thereof, said fuel passages communicating 95 with the combustion chamber of the engine, a power piston and a sub-piston both arranged to reciprocate within said cylinder, a cross-head, means connecting said power piston to said cross-head and means connected directly to said cross-head for permitting movement of said pistons at the same initial rate of speed without relative movement and for causing, subsequently, positive relative movement between the same.
9. An internal combustion engine com- 100
- 105
- 110
- 115
- 120
- 125
- 130

trolling said sub-piston positively during a substantial portion of the cycle and for retarding its speed near the end of its stroke, a member connecting said means to said 5 cross-head, and means connecting said power piston to said cross-head.

In testimony whereof, I have hereunto

subscribed my name this 22nd day of April, 1916.

RICHARD F. GILE.
